Term of patent 14 years

(Cl. D45—4)

FIG.1

FIG.3

FIG. 1 is a plan view of an expansible link chain for a bracelet showing my new design;

FIG. 2 is a side elevation of the chain illustrated in FIG. 1;

FIG. 3 is an enlarged top perspective view of a portion of one of the links thereof.

The dominant features of my design reside in the portions shown in full lines.

I claim:

The ornamental design for an expansible link chain for a bracelet or the like, as shown and described.
